SPROCKET DEVICE

Louis A. McNabb, Glenview, Ill., assignor to Bell & Howell Company, Chicago, Ill., a corporation of Illinois

Application June 8, 1945, Serial No. 598,385

14 Claims. (Cl. 74—243)

1

My invention relates to perforated film feed sprocket devices of motion picture machines, although not limited to this use alone, and has particular relation to such devices involving a sprocket having sprocket teeth only at one end thereof.

Objects of the invention reside in the provision of a novel and effective guide means for releasably retaining a perforated strip engaged on a sprocket, which prevents punching or embossing of the strip by reason of the guide being pressed against the outer face of the strip while the strip rides on top of the teeth of the sprocket, which is convenient in engaging the strip on and removing the same from the sprocket, and which is inherently of an unobtrusive and simple appearance.

The invention will be better understood by reference to the accompanying drawing forming a part hereof and in which—

Figures 1 and 2 are sectional views of a sprocket device embodying my invention and taken on the line 1—1 of Figure 3, these views showing parts in different positions;

Figure 3 is an end elevation of the sprocket device; and

Figure 4 is a view in elevation similar to that of Figure 3 and having parts of the structure shown in section.

Referring to the drawing, 1 designates a support or frame which is provided with a circular recess 2, and an annular support member 3 is secured in this recess and forms a part of the support or frame. See Figures 1 and 2. The member 3 is counterbored inwardly from the outer face thereof to form a circular recess 4.

A spindle 5 is rotatably mounted on the support 1 through the medium of a bushing 6, and this spindle is disposed concentrically of the recess 4 and projects through this recess and outwardly of the support. A film sprocket 7 is secured on the projecting end of the spindle 5 by means of a set screw 8, the sprocket being disposed in projecting relation with the support and being rotatable with the spindle which is driven in a usual manner.

A strip retaining guide 9 of circular disk form is disposed in the region of the inner end of the sprocket 7 and extends between the support member 3 and the sprocket 7 transversely of and across the sprocket axis and is provided with a central bore 11 through which the spindle 5 and an inwardly projecting hub 12 of the sprocket passes. The guide 9 is mounted in the recess 4 for movement axially of the sprocket 7, and a

2

stop ring 13 is secured on the outer face of the support member 3 in concentric relation therewith and overlies the marginal portion of the recess 4 and is thus engageable by the marginal portion of the guide 9 to limit outward movement of the guide. Rotation of the guide 9 is prevented by a guide pin 14 secured on the support member 3 in parallel relation with the spindle 5 and slidably engaging in an aperture 15 through the guide.

The central portion of the guide 9 is offset outwardly axially of the guide, as designated at 16, and projects into an annular channel 17 in the inner end portion of the sprocket 7; this offset portion 16 affording considerable space between it and the outer end of the bushing 6. A helical compression spring 18 encircles the spindle 5 and hub 12 between the offset portion 16 and the bushing 6 and is operative between this offset portion and bushing to yieldably urge the guide 9 axially of the sprocket 7 and outwardly into engagement with the stop ring 13, as shown in Figure 1, the guide being movable, against the influence of this spring, inwardly axially of the sprocket into the position shown in Figure 2.

The sprocket 7 is provided with sprocket teeth 19 only in the region of its inner end, and the sprocket is also provided with a strip edge engaging shoulder 21 in the region of its outer end 30 and facing toward its inner end. A strip 22, such as a motion picture film strip provided with feed perforations 23, is engaged on the sprocket with feed perforations of the strip engaged on teeth of the sprocket for feeding the strip, the annular shoulder 21 being engageable with the opposing edge of the strip for laterally guiding the same in one direction, and guide rollers 24 carried on the support 1 serving to guide the strip to and from the sprocket, as shown in Figures 3 and 4.

The guide 9 is provided with an arcuate portion 25 extending correspondingly with the periphery of the sprocket 7 and the internal surface 26 of this portion provides a guide surface facing radially of and toward the sprocket axis 45 and engageable with the outer face of the strip 22 engaged on the sprocket to retain the feed perforations of the strip in engagement with the sprocket teeth when the guide 9 is positioned by the spring 18 and stop ring 13 in its strip guiding position as shown in Figure 1. The outer face 27 of the guide 9 immediately inward of the surface 26 provides a strip edge engaging guide surface facing toward the shoulder 21 of the sprocket and cooperating with this shoulder in laterally guiding the strip therebetween when the

guide 9 is in its strip guiding position. Movement of the guide 9 inwardly from the position thereof shown in Figure 1 positions the guide out of strip guiding position as shown in Figure 2 in which position of the guide the strip may be conveniently engaged on or removed from the sprocket.

The external surface 28 of the arcuate portion 25 of the guide 9 provides a cam surface which is inclined with respect to the sprocket axis and faces in the direction of the outer end of the sprocket 7 and radially outward of the sprocket axis and is engageable by the opposing edge of the strip 22 as an incident of engaging the strip on the sprocket to actuate the guide out of strip guiding position against the influence of the spring 18 and permit engagement of the strip on the sprocket, the spring 18 being comparatively weak and the fitting of the guide 9 with the parts engaged thereby being sufficiently loose to permit canting of the guide for this purpose. After the strip is engaged on the sprocket, the spring automatically actuates the guide into strip guiding position. Thus, engagement of the strip on the sprocket is an extremely simple and convenient operation.

Obviously, the portion 25 of the guide cannot press against the outer face of the strip 22 while the strip rides on top of the teeth of the sprocket so that punching or embossing of the strip is prevented.

The outer end of the sprocket 7 is concentrically counterbored, as designated at 29, and a push plunger head 31, at the outer end of the sprocket, is mounted within this counterbore for reciprocation axially of the sprocket and is accessible for manual depression as by a person's finger 32 as shown in Figure 2. Three plunger rods 33 extend within the sprocket 7 and are arranged in parallelism with and spaced about the sprocket axis exteriorly of the spindle and are mounted for reciprocation axially of the sprocket in bores 34 through the sprocket. See Figures 1, 2 and 4.

The outer ends of the rods 33 are secured with the plunger head 31 and the inner ends of these rods are secured with a ring 35 slidably mounted in the annular channel 17 of the sprocket and disposed outwardly of the central offset portion 16 of the guide 9 and engageable axially of the sprocket inwardly against the offset portion 16, this assembly forming a push plunger device mounted for reciprocation within and axially of the sprocket and operative on the guide 9 axially of the sprocket for actuating the guide inwardly out of strip guiding position by manual depression of the plunger head 31 as shown in Figure 2, thus providing for conveniently positioning the guide out of strip guiding position for removing the strip 22 from the sprocket 7 and, if desired, for engaging the strip on the sprocket. A helical compression spring 36 encircles the extreme outer end of the spindle 5 and is arranged within opposing recesses 37 and 38 respectively in the sprocket 7 and plunger head 31, and is operative between the sprocket and plunger head to yieldably urge the push plunger device outwardly, as shown in Figure 1, independently of the spring 18, thus not necessitating the spring 18 being sufficiently strong to actuate the push plunger device outwardly.

While I have thus described my invention, I do not wish to be limited to the precise details described, as changes may be readily made without departing from the spirit of my invention,

but having thus described my invention, I claim as new and desire to secure by Letters Patent the following:

1. In a sprocket device, the combination with a support, of a revoluble sprocket carried therewith in projecting relation with the same and provided with sprocket teeth in the region of its inner end, a strip retaining guide disposed in the region of the inner end of said sprocket and provided with a guide surface facing radially of and toward the sprocket axis and engageable with the outer face of a perforated strip engaged on said sprocket, and said guide being mounted for movement axially of said sprocket into and out of strip guiding position.

2. In a sprocket device, the combination with a support, of a revoluble sprocket carried therewith in projecting relation with the same and provided with sprocket teeth in the region of its inner end and with a strip edge engaging annular shoulder in the region of its outer end and facing toward its inner end, a strip retaining guide disposed in the region of the inner end of said sprocket and provided with a guide surface facing radially of and toward the sprocket axis and engageable with the outer face of a perforated strip engaged on said sprocket and with a second strip edge engaging guide surface facing toward said shoulder, and said guide being mounted for movement axially of said sprocket into and out of strip guiding position.

3. In a sprocket device, the combination with a support, of a revoluble sprocket carried therewith in projecting relation with the same and provided with sprocket teeth only in the region of its inner end and with a strip engaging annular shoulder in the region of its outer end and facing toward its inner end, a strip retaining guide disposed in the region of the inner end of said sprocket and provided with a guide surface facing radially of and toward the sprocket axis and engageable with the outer face of a perforated strip engaged on said sprocket and provided with a strip edge engaging guide surface facing toward said shoulder, said guide being mounted for movement axially of said sprocket into and out of strip guiding position and being yieldably urged into strip guiding position, and stop means limiting movement of said guide into strip guiding position.

4. In a sprocket device, the combination with a support and a spindle mounted thereon and projecting therefrom, of a revoluble sprocket carried on said spindle in projecting relation with said support and provided with sprocket teeth in the region of its inner end, a strip retaining guide disposed in the region of the inner end of said sprocket and extending between said support and sprocket transversely of and across the sprocket axis and provided with an opening through which said spindle passes and provided with a guide surface facing radially of and toward the sprocket axis and engageable with the outer face of a perforated strip engaged on said sprocket, said guide being mounted for movement axially of said sprocket into and out of strip guiding position, spring means operative to yieldably urge said guide into strip guiding position, and stop means limiting movement of said guide into strip guiding position.

5. In a sprocket device, the combination with a support provided with a recess and a spindle mounted on said support and projecting therefrom centrally of said recess, of a revoluble sprocket carried on said spindle in projecting

relation with said support and provided with sprocket teeth in the region of its inner end, a strip retaining guide disposed in the region of the inner end of said sprocket and extending between said support and sprocket transversely of and across the sprocket axis and provided with an opening through which said spindle passes and provided with a guide surface facing radially of and toward the sprocket axis and engageable with the outer face of a perforated strip engaged on said sprocket, said guide being mounted in said recess for movement axially of said sprocket into and out of strip guiding position, a helical compression spring encircling said spindle and operative to yieldably urge said guide into strip guiding position, and stop means limiting movement of said guide into strip guiding position.

6. In a sprocket device, the combination with a support provided with a recess and a spindle mounted on said support and projecting therefrom centrally of said recess, of a revoluble sprocket carried on said spindle in projecting relation with said support and provided with sprocket teeth only in the region of its inner end and provided with a strip engaging annular shoulder in the region of its outer end and facing toward its inner end, a strip retaining guide disposed in the region of the inner end of said sprocket and extending between said support and sprocket transversely of and across the sprocket axis and provided with an opening through which said spindle passes and provided with a guide surface facing radially of and toward the sprocket axis and engageable with the outer face of a perforated strip engaged on said sprocket and provided with a strip edge engaging guide surface facing toward said shoulder, said guide being mounted in said recess for movement axially of said sprocket into and out of strip guiding position, a helical compression spring encircling said spindle and operative between said support and guide to yieldably urge said guide into strip guiding position, and a stop ring secured on said support and overlying the marginal portion of said recess and engageable by said guide to limit movement of said guide into strip guiding position.

7. In a sprocket device, the combination with a support, of a revoluble sprocket carried therewith in projecting relation with the same and provided with sprocket teeth in the region of the inner end thereof, a strip retaining guide disposed in the region of the inner end of said sprocket and provided with a guide surface facing radially of and toward the sprocket axis and engageable with the outer face of a perforated strip engaged on said sprocket, said guide being mounted for movement axially of said sprocket into and out of strip guiding position, and means for positioning said guide in and out of strip guiding position comprising an actuating device mounted for reciprocation within and axially of said sprocket and accessible for manual actuation at the outer end of said sprocket.

8. In a sprocket device, the combination with a support, of a revoluble sprocket carried therewith in projecting relation with the same and provided with sprocket teeth in the region of the inner end thereof, a strip retaining guide disposed in the region of the inner end of said sprocket and provided with a guide surface facing radially of and toward the sprocket axis and engageable with the outer face of a perforated strip engaged on said sprocket, said guide being mounted for movement axially of said sprocket

into and out of strip guiding position, spring means yieldably urging said guide into strip guiding position, and a push plunger device mounted for reciprocation within and axially of said sprocket and operative on said guide axially of said sprocket for actuating said guide out of strip guiding position and accessible for manual depression at the outer end of said sprocket.

9. In a sprocket device, the combination with a support and a spindle mounted thereon and projecting therefrom, of a revoluble sprocket carried on said spindle in projecting relation with said support and provided with sprocket teeth in the region of its inner end, a strip retaining guide disposed in the region of the inner end of said sprocket and extending between said support and sprocket transversely of and across the sprocket axis and provided with an opening through which said spindle passes and provided with a guide surface facing radially of and toward the sprocket axis and engageable with the outer face of a perforated strip engaged on said sprocket, said guide being mounted for movement axially of said sprocket into and out of strip guiding position, spring means operative to yieldably urge said guide into strip guiding position, and a push plunger device mounted for reciprocation within and axially of said sprocket and operative on said guide axially of said sprocket for actuating said guide out of strip guiding position and comprising a plurality of plunger rods extending within said sprocket and arranged in parallelism with and spaced about the sprocket axis exteriorly of said spindle and a head at the outer end of said sprocket and accessible for manual depression and operative on said rods.

10. In a sprocket device, the combination with a support provided with a recess and a spindle mounted on said support and projecting therefrom centrally of said recess, of a revoluble sprocket carried on said spindle in projecting relation with said support and provided with sprocket teeth only in the region of its inner end and provided with a strip engaging annular shoulder in the region of its outer end and facing toward its inner end, a strip retaining guide disposed in the region of the inner end of said sprocket and extending between said support and sprocket transversely of and across the sprocket axis and provided with an opening through which said spindle passes and provided with a guide surface facing radially of and toward the sprocket axis and engageable with the outer face of a perforated strip engaged on said sprocket and provided with a strip edge engaging guide surface facing toward said shoulder, said guide being mounted in said recess for movement axially of said sprocket into and out of strip guiding position, spring means operative to yieldably urge said guide into strip guiding position, stop means limiting movement of said guide into strip guiding position, and a push plunger device mounted for reciprocation within and axially of said sprocket and operative on said guide axially of said sprocket for actuating said guide out of strip guiding position comprising a plurality of plunger rods extending within said sprocket and arranged in parallelism with and spaced about the sprocket axis exteriorly of said spindle and a head at the outer end of said sprocket and accessible for manual depression and operative on said rods.

11. In a sprocket device, the combination with a support, of a revoluble sprocket carried there-

with in projecting relation with the same and provided with sprocket teeth in the region of its inner end, a strip retaining guide disposed in the region of the inner end of said sprocket and provided with a guide surface facing radially of and toward the sprocket axis and engageable with the outer face of a perforated strip engaged on said sprocket, said guide being mounted for movement axially of said sprocket into and out of strip guiding position and being yieldably urged into strip guiding position, stop means limiting movement of said guide into strip guiding position, and said guide being further provided with a cam surface disposed radially of the sprocket outwardly of said guide surface and inclined with respect to the sprocket axis and facing in the direction of the outer end of said sprocket and radially outward of the sprocket axis and engageable by the opposing edge of said strip as an incident of engaging said strip on said sprocket to actuate said guide out of strip guiding position.

12. In a sprocket device, the combination recited in claim 3 and further characterized in combination in that said guide is further provided with a cam surface disposed radially of the sprocket axis outwardly of said first mentioned guide surface and inclined with respect to the sprocket axis and facing in the direction of the outer end of said sprocket and radially outward of the sprocket axis and engageable by the opposing edge of said strip as an incident of engaging said strip on said sprocket to actuate said guide out of strip guiding position.

13. In a sprocket device, the combination recited in claim 8 and further characterized in combination in that said guide is further provided with a cam surface disposed radially of the sprocket axis outwardly of said guide surface and inclined with respect to the sprocket axis and facing in the direction of the outer end of said sprocket and radially outward of the sprocket axis and engageable by the opposing edge of said strip as an incident of engaging said strip on said sprocket to actuate said guide out of strip guiding position, and that a second spring means yieldably urges said push plunger device in the direction corresponding with movement of said guide into strip guiding position.

14. In a sprocket device, the combination recited in claim 10 and further characterized in combination in that said guide is further provided with a cam surface disposed radially of the sprocket axis outwardly of said first mentioned guide surface and inclined with respect to the sprocket axis and facing in the direction of the outer end of said sprocket and radially outward of the sprocket axis and engageable by the opposing edge of said strip as an incident of engaging said strip on said sprocket to actuate said guide out of strip guiding position, and that a second spring means yieldably urges said push plunger device in the direction corresponding with movement of said guide into strip guiding position.

LOUIS A. McNABB.
